UNITED STATES PATENT OFFICE

HENRI A. BRYSELBOUT, OF DETROIT, MICHIGAN, ASSIGNOR TO COPELAND PRODUCTS, INC., A CORPORATION OF MICHIGAN

EXPANSION ELEMENT

Application filed January 18, 1928. Serial No. 247,580.

This invention relates to refrigerating mechanism and particularly to the cooling elements or expansion chambers employed in connection with the same, the principal object being the provision of a device of this type which will more rapidly absorb heat from the chamber to be cooled than in conventional constructions.

Another object is the provision of a cooling element in which heat conducting fins are formed to simulate a plurality of stack like structures through which a flow of air or other heat conducting medium to be cooled will be caused to occur similar to the manner in which a draft occurs in the stacks of furnaces.

A further object is to provide an expansion chamber for a refrigerating mechanism comprising a box-like member of heat conducting material having an open top and bottom and adapted to be supported from a floor or other support with the lower edges thereof out of contact with the floor, transversely vertically extending partitions of heat conducting material being provided between the sides of the member, and refrigerant passage being secured in thermal contact with the sides of the member.

The above being among the objects of the present invention the same consists in certain features of construction and combinations of parts to be hereinafter described with reference to the accompanying drawing, and then claimed, having the above and other objects in view.

In the accompanying drawing which illustrates a suitable embodiment of the present invention and in which like numerals refer to like parts through the several different views:

Fig. 1 is a transverse vertical sectional view through a butcher's counter, indicating the relative position of a refrigerator cooling unit constructed in accordance with the present invention and in connection therewith.

Fig. 2 is an enlarged sectional view of the expansion or cooling unit shown in Fig. 1 taken on the line 2—2 of Fig. 1.

Fig. 3 is a sectional view taken on the line 3—3 of Fig. 2.

The present invention is a modification of

the construction shown described in my application for Letters Patent of the United States for improvements in refrigerating mechanism filed on even date herewith, and relates particularly to a modification of that construction particularly adaptable for use in connection with the refrigeration of display cases or counters of the type generally employed in butcher shops and the like.

Such counters or display cases usually comprise the lower chamber 10 having a bottom 11, front 12 and top 13. A display case including a transparent front face 14, a transparent top face 15 and a transparent movable rear face 16 is supported on the top wall 13 and adapted to form a compartment 17 in which food stuffs may be displayed to the view of the customer. The rear face 16 of the case is generally of a much less depth than the depth of the chamber 17 and a shelf or counter member 18 extends rearwardly therefrom and upon which the butcher may wrap meat or employ for other purposes. A cover 19 hinged to the rear edge of the counter 18 by hinges 20 or other suitable means is provided to close the rear face of the chamber 17. In the application of a mechanical refrigerator to a display case of this type an expansion or cooling element is positioned in the chamber 17 below the counter 18 and is connected by suitable tubing to the mechanism which is generally positioned in the lower chamber 10. The refrigerating mechanism may be of either the absorption or adsorption type or may be of the mechanical compression type

such as indicated in drawing and which may comprise a base 21 slidably received on the bottom 11 and on which is secured the compressor 22, an electric motor 23, fan 24, condenser 25 and receiver 26. The fan 24 is shown as connected directly to the shaft of the motor 23 and the compressor 22 is driven from the motor 23 by the belt 27 in a conventional manner. The outlet side of the compressor is connected by a tube 28 to the condenser 25 which in turn is connected by the tube 29 to the receiver 26. The receiver 26 is connected by the tube 30 to an automatic expansion valve 31 or other suitable device which will automatically meter the flow of

refrigerant from the receiver 26 to the cooling element.

The cooling or expansion element which forms the subject matter of the present invention and which is supported on the wall 13 below the counter 18 comprises a box-like member of heat conducting material having side walls 32 and end walls 33, the top and bottom being open. Legs such as 34 which 5 may be formed integral with the box-like member or separately therefrom are provided for supporting the box-like member above the wall 13 so as to permit passage of air below the same. The height of the box-like 10 member is less than the vertical distance between the wall 13 and counter 18 so that the top of the member is spaced freely from the underside of the counter 18 when in position. Extending between the side walls 32 are a 15 plurality of vertically extending spaced transverse members 35 which preferably extend from the top of the walls 32 to the bottom thereof and act to separate the same into a plurality of stack-like structures or compartments. The members 35 which thus serve as partitions are formed of heat conducting material and are preferably provided with end flanges 36 soldered to the walls 32 or otherwise secured to the same in thermal 20 contact therewith. One or more tubes are wound around the outside of the walls 32 and 33 and are soldered to the same throughout their length so as to be in thermal contact therewith. Although shape or manner of securing 25 this tubing to the walls 32 and 33 is more or less immaterial to the proper functioning of the device, it is shown in the drawing as comprising a single tube 37 which is wound around the outside of the box-like member so 30 as to form a plurality of turns upon the same which turns are in thermal contact with the walls 32 and 33 throughout their length, as by being soldered thereto. One end of the tube 37 is connected by a tube such as 38 to the 35 expansion valve 31, and the other end of the tube 37 is connected by the tube 39 to the intake side of the compressor. Although the section of the tube is more or less immaterial, it is preferable that the same is flattened as 40 shown with the flattened side thereof secured to the walls 32 and 33 in order to provide a greater area of thermal contact therewith. The rear edge of the wall 13 is preferably provided with a notch 41 through which the 45 tubes 38 and 39 may extend so that upon opening the door 19 both the base 21 with all its mechanism and the expansion element coil may be removed without breaking the connection between them.

50 The result of this construction is that a plurality of stack-like structures are formed which because they are formed from heat conducting material and are in thermal contact with the refrigerant carrying tube 37 55 conduct the heat of the air within the chamber 17 to the refrigerant within the tube 37. This causes the air in contact with the walls 32 and 33 and partitions 37 to be cooled and in cooling to move downwardly because of its relatively increased weight, thus drawing in 60 warm air at the top of the device and discharging the cold air at the bottom of the same. This action, because of the stack-like structures, creates what may be termed a draft and a flow of air is induced vertically 65 downward at a relatively greater speed than in the case where cooling elements having simple fin structures are employed. This increase of speed of the air through the cooling element permits a greater rate of heat transfer for a given size and weight of unit and thereby permits a smaller and less expensive unit to be used.

It is preferable in employing this construction that a baffle 40 be positioned between the forward edge of the counter 18 and the wall 13 and spaced from the same at both the top and bottom whereby the air in the chamber 17 will be caused to flow into the space below the counter 18 at the top thereof and the air from the cooling element will be discharged from the bottom, thus setting up a circulation of air in the chamber 17 which will increase the rate at which it may be cooled.

Although I have shown a simple form of box-like member and a simple manner of securing the refrigerant carrying passage to the same, it will be apparent that these features may be readily changed by one skilled in the art to suit his particular problem or desires without materially altering the invention herein covered, and formal changes may be made in the specific embodiment of the invention described without departing from the spirit or substance of the broad invention, the scope of which is commensurate with the appended claims.

What I claim is:

1. In a device of the class described, an elongated box-like member of heat conducting material having an open top and bottom, vertically extending members of heat conducting material extending between the sides of said member and in thermal contact therewith, and a refrigerant passage in thermal contact with said member.

2. In a device of the class described, a box-like member of heat conducting material having an open top and bottom, vertically extending partitions of heat conducting material extending between the sides of said member in thermal contact therewith and dividing the interior thereof into a plurality of separate stack-like structures, and a refrigerant passage in thermal contact with said member.

3. In a device of the class described, an elongated box-like member of heat conducting material having an open top and bottom, vertically extending partitions extending between the sides of said member and secured

in thermal contact therewith, and a refrigerant passage secured to a side wall of said member and in thermal contact therewith for substantially the entire length of said wall.

4. In a device of the type described, an elongated box-like structure of heat conducting material having an open top and bottom, a plurality of plates of heat conducting material extending between the sides of said member and in thermal contact therewith, said plates extending vertically between the top and bottom of said member, and a refrigerant passage comprising a plurality of loops surrounding said member and secured in thermal contact therewith for substantially its entire length.
